UNITED STATES PATENT OFFICE

1,978,810

HYDRAULIC APPARATUS

Lewis Ferry Moody, Princeton, N. J.

Original application February 28, 1928, Serial No. 257,615. Divided and this application August 12, 1931, Serial No. 556,572.

5 Claims. (Cl. 253—117)

This invention relates to hydraulic apparatus and more particularly to draft tubes of hydraulic turbines. It has for certain of its objects to provide not only an improved relation between the entrance and discharge passages of the draft tube but also to provide improved simplified forms of these passages and of the connection between the same whereby desirable characteristics of both the elbow and spreading types of draft tubes are had, thus obtaining efficient deceleration of a regain of whirl energy in the fluid while turning and conducting the same from the turbine runner in a relatively small and laterally confined space.

Other objects and advantages will be apparent from the following description of the accompanying drawings, in which:

- Fig. 1 is a section taken on line 1—1 of Fig. 2;
- Fig. 2 is a horizontal sectional view taken on line 2—2 of Fig. 1;
- Fig. 3 is a vertical sectional view taken on line 3—3 of Fig. 2;
- Fig. 4 is a vertical sectional view on line 4—4 of Fig. 2;
- Fig. 5 is a horizontal sectional view of a modification taken on line 5—5 of Fig. 6;
- Fig. 6 is a vertical sectional view taken on lines 6—6 of Fig. 5;
- Fig. 7 is a vertical sectional view taken on lines 7—7 of Fig. 5; and
- Fig. 8 is a vertical sectional view taken on line 8—8 of Fig. 5.

In the drawings the various forms of draft tubes are shown as applicable to a vertical shaft turbine (not shown) although it will of course be understood that these draft tubes may also be employed with horizontal shaft turbines. It also will be clear from the disclosure herein that the draft tubes may be used with any of the different types of turbines such as of the propeller or Francis type which are well-known and therefore need not be described or disclosed in detail. It will suffice to say that the flow in leaving the turbine runner enters the entrance or primary passage 1 of the draft tube and from which the flow is turned and passes through a transition space somewhat in the nature of a spreading collector or transition passage 2 surrounding the entrance or primal portion of the draft tube and thence flows to tailwater. The primary passage as shown is formed of an outer wall having a slightly tapered conical or upper portion 4 gradually curved outward in a substantially horizontal direction at its lower end to form at least a partial bell-mouth 3. The primary draft tube serves to direct the flow downward from the turbine run-

ner and outwardly into a horizontal plane. The cross sectional area of this tube as shown increases gradually so as to give a gradual deceleration to the meridian components of the flow and at the same time the tube is adapted to handle efficiently flow containing whirling components about the turbine axis.

The passage 2 starts at the mouth of the draft tube, curving entirely around the axis of the draft tube and terminating in the horizontal straight discharge passage 5 having a direction downstream and radial to the draft tube. The outer wall of the transition passage is vertical as shown.

The horizontal discharge passage 5 for discharging the direct flow from the collector passage 2 to tailwater is substantially rectangular in cross section, having a horizontal floor 6 extending from the collector passage, the top or roof wall 6' of which is inclined upwardly at an angle of about 20° with the floor and substantially parallel vertical side walls 7 and 8. Starting from the central portion of the top or roof 6 as shown at 9 in Fig. 4 the roof laterally slopes upwardly at a similar angle. While in this form the entrance passage is disposed symmetrically relative to the center of the discharge passage, instead of being offset, yet the bell-mouth is a surface of revolution except for the portion thereof eliminated by the intersecting substantially vertical upstream wall 2' of the horizontal passage.

In the embodiment of the invention illustrated in Figs. 5 to 8, the flow leaving the turbine runner enters the primary draft tube, which forms a vertical passage 10, is turned and passes through a collector or transition passage 11 concentric to the primary draft tube, and thence to tailwater. The primary draft tube as shown is formed of an outer wall 12 having a slightly tapered conical or upper portion 13, is gradually curved outward in a substantially horizontal direction at its lower end. Projecting upwardly from the floor 14 of the collector passage 11 into the flaring end of the wall 12 and concentric therewith is a cone 15, whose concave surface is formed in relation to the outline of the end wall 12. The outer wall 12 and cone 15, together form a primary draft tube which serves to direct the flow downward from the turbine runner and outward into a horizontal plane.

Collector passage 11 begins at the mouth of the draft tube and is concentric therewith, curving entirely around the axis of the draft tube and terminating in the horizontal straight discharge passage 16. The outer wall of the col-

105

110

lector passage is vertical and its inner wall is formed by a portion of the cone 15.

The horizontal discharge passage 16 for discharge of the flow from the collector passage 11 to tailwater is substantially rectangular in cross section and has a floor 14 and a roof 17 inclined upwardly at an angle of approximately 20° with the floor. Vertical side walls 18 and 19 are substantially parallel. A pier or partition 20 divides the passage and supports the roof. When the downstream length of the discharge passage is restricted the angle of the top wall can be slightly increased, but should not be increased too much to avoid loss of head and efficient deceleration.

Starting from the central portion of the roof 17, the roof as shown at 21 in Fig. 8 also laterally, slopes upwardly at an angle of approximately 20°. Draft tube stay vanes 22 may be used or omitted as the occasion demands. In this modification, as in the other, at least the initial portion of the bell-mouth of the primary or entrance passage extends substantially around 360°. In this form the bell-mouth is not intersected by the collector wall but instead the wall 23 commences at substantially the outer limits of the bell-mouth, that is, at the point where its outer and upper wall becomes horizontal and of minimum height above the floor. In each case however the upstream wall is disposed sufficiently upstream beyond the bell-mouth so that the bell-mouth has at least a portion extending upstream as in Fig. 1 or entirely upstream as in Fig. 6. Also the height of the discharge passage at its upstream end is not greater than the height of the lowermost portion of the bell-mouth.

In either case however the cross-sectional areas of the passage before, during and after passing around the bend are proportioned so as to effect the same velocity relations as set forth in my copending application Serial No. 257,615, filed February 28, 1928, Patent No. 1,853,138, which is directed generally to the form of draft tube having an offset relation between the entrance and discharge passages while the present invention is directed to an improved relation between the entrance passage and the discharge passage.

I claim:

1. A draft tube turning from an axial direction at its inlet to a radial direction at its discharge and comprising an entrance passage terminating in an outwardly flaring bell-mouth formed as a surface of revolution coaxial with the entrance passage and of uniform height above the floor, a discharge passage, a collector passage connecting said entrance and discharge passages and provided with an upstream wall so disposed beyond the bell-mouth that the bell-mouth extends

upstream without being intersected by the upstream wall, said wall extending downstream to form the sides of the discharge passage, and the height of the collector passage at its upstream end being not greater than the height of the lower portion of the bell-mouth.

2. A draft tube comprising an entrance passage terminating in a bell-mouth formed as a surface of revolution, and a passage leading therefrom provided with a substantially vertical upstream wall disposed beyond the bell-mouth without intersecting the same and having a height at its upstream end not greater nor less than the height of the lower end of the bell-mouth at its downstream end.

3. A draft tube comprising an entrance passage terminating in an outwardly flaring bell-mouth formed as a surface of revolution, a collector passage receiving flow from said entrance passages provided with an upstream wall disposed beyond the bell-mouth without intersecting the same, and a discharge passage, said wall continuing downstream to form the sides of said discharge passage and said discharge passage having a greater depth along at least one side than at its central portion.

4. A draft tube comprising an entrance passage terminating in a bell-mouth, the entrance passage and bell-mouth being formed as a surface of revolution, a collector passage provided with a floor and a substantially vertical upstream wall disposed beyond the bell-mouth, so as not to intersect the same, the collector passage at its upstream end having a height not greater than the height of the lower end of the bell-mouth from said floor, and a cone formed as a surface of revolution concentric with said other surface projecting upwardly from said collector passage into said entrance passage.

5. A draft tube comprising an entrance passage terminating in a bell-mouth, the entrance passage and bell-mouth being formed as a surface of revolution, a collector passage provided with a floor and an upstream wall so disposed with respect to the bell-mouth without intersecting the same that the bell-mouth provides a terminus, for the entrance passage, of substantially uniform height from the floor of the collector passage, and a discharge passage leading from said collector passage and having relatively diverging floor and roof, said discharge passage having at least one point thereof of relatively shallow depth not greater than the initial radius of the entrance passage and said discharge passage also having a minimum width at least three times its minimum depth.
